(57) **CLAIM**

The ornamental design for a quick release trigger lock assembly, as shown and described.

DESCRIPTION

FIG. 1 is a perspective view of the quick release trigger lock assembly taken from approximately a 45 degree raised side view, with the quick release trigger lock assembly shown as an upper and lower component being installed onto a firearm, in accordance with the present invention;

FIG. 2 is a perspective view of the quick release trigger lock assembly depicted in FIG. 1, taken from approximately a 45 degree raised side view without the firearm in place;

FIG. 3 is a top view of the quick release trigger lock assembly depicted in FIG. 1;

FIG. 4 is a side view of the quick release trigger lock assembly depicted in FIG. 1;

FIG. 5 is a bottom view of the quick release trigger lock assembly depicted in FIG. 1, with the lower component removed.

The broken lines in the drawings are provided for environment and depict unclaimed portions of the quick release trigger lock assembly and/or an unclaimed exemplary firearm with which the quick release trigger lock assembly is used. The broken lines form no part of the claimed design.
